UNITED STATES PATENT OFFICE.

MATTHEW H. LOUGHRISE, OF BOGOTA, NEW JERSEY.

ELECTRIC CIRCUIT.

1,242,457.

Specification of Letters Patent.

Patented Oct. 9, 1917.

Application filed July 17, 1916. Serial No. 109,652.

To all whom it may concern:

Be it known that I, MATTHEW H. LOUGHRISE, naturalized, a citizen of the United States, and a resident of Bogota, county of Bergen, and State of New Jersey, have invented certain new and useful Improvements in Electric Circuits, of which the following as a specification.

This invention relates to electric circuits and more particularly to a compound arrangement of circuits in which characteristics may be introduced into the conductors of said circuit at various points to vary the operation of an electric translating device in 15 said circuit.

The objects of this invention are to vary the operation of an electric translating device by changing certain characteristics in one or both conductors of the circuit controlling said translating device, also to vary its operation by changing the characteristics in said conductors at different points, also to prevent false operation of a remote controlled device from foreign current. Other 25 objects of this invention will appear in the following specification.

I will now describe the embodiment of my invention illustrated in the accompanying drawing, and will thereafter point out my 30 invention in claims.

This drawing shows a variety of applications of my invention, any or all of which may be used in combination or each may be used separately.

35 The present invention is applied to a circuit arrangement having an auxiliary or superposed circuit which normally remains deenergized or inactive when the currents in each conductor of the first circuit are 40 balanced or bear a fixed relation to each other, and when these conditions are not established, the superposed circuit becomes effective to vary the effects obtained from the other circuit.

45 In the drawings I have shown four distinct arrangements of circuits at A, B, C and D, each of which utilizes my invention and are herein referred to as application A, application B, application C and application 50 D respectively.

I have illustrated my invention in connection with the operation of a crossover between two tracks to insure safety and precision in circuits for this purpose. This, 55 however, is only a matter of convenience, as the principle of my invention may be ap-

plied to electric circuits for any purpose whatsoever.

Referring to Figure 1, the crossover *a*—*b*, between tracks *c*—*d*, is operated by power 60 controlled by lever 90; a movement of the lever requiring a corresponding movement of the crossover at both ends. Application B, shows the circuits controlling the mechanism for operating the crossover and application A, shows the circuits operating an electric lock which restricts the movement of said lever until the ends of the crossover have first completed their movement. Application C, is a development from application 70 A, in which a relay controlling a signaling device responds to the operation of both ends of the crossover and to the movement of the controlling lever and, application D, is a modification in which corresponding results may be obtained by controlling the circuit on one of its 75 controlling wires instead of both as in the other applications. Each of these circuits also incorporates a principle whereby a 80 false operation of the controlled apparatus cannot be obtained from current from any foreign source.

In the illustration, 51 and 52 are the mains of a power supply system to which transformer 53 is connected, feeding transmission mains 54 and 55 to which the sub-mains 56 and 57 are connected and to these wires the primary of transformers 58 and 59 are connected as shown.

The main circuit operating magnet 85, application A, may be traced from the secondary of transformer 58, wire 70, resistance 81, switch 210, wire 71, resistance 80, switch 211, wire 72 to magnet 85 and return 95 by wire 76, switch 211, resistance 81, wire 75, switch 210, resistance 80 and wire 74 to transformer, thus energizing this magnet. It will be seen that an auxiliary or superposed circuit is formed from a central point 100 of transformer 58 which connects to wire 60, and by wires 55, 62 and 65 connects to safety magnet 86, the other side of this magnet connecting by wire 78 to an intermediate point in the winding of magnet 85, through which it makes connection to wires 105 72 and 76 and back to the outer terminals of the transformer. Push buttons 48 may be introduced in wires 72 and 76 to maintain magnet 85 normally deenergized as 110 shown. The resistance coils indicated by the reference character 80 are similar, and

those indicated by the character 81 are similar, but the former have a greater resistance value than the latter; these are referred to as major resistances, while the coils 81 are referred to as minor resistances.

When the conditions are such that the potential at the middle connection of the transformer to wire 60 is equal to the potential of the main circuit where wire 78 connects to magnet 85, there can be no flow of current between these points and, consequently, magnet 86 is not energized. On the other hand, if the potentials at these points are not equal there will be a flow of current in the auxiliary circuit to energize magnet 86. This may happen when, for instance, there is an unequal flow of current in each side of the main circuit operating magnet 85 and which may arise from a difference in the resistance or reactance in each side of this circuit, or a difference in potential in each side of the transformer 58, that is, when the connection to wire 60 is not made to a central point in the transformer; or it may arise when current leaks from or to either side of the main circuit from or to another circuit such as a cross y , between wires 75 and 171.

The action of this unbalancing may be traced as follows:—Assume that the current in wire 75 is greater than in wire 71, this current traverses the circuit to magnet 85 and to wire 78 where it divides in proportion to the resistance of the various circuits, the excess flows through magnet 86, wire 65 and wire 62 to wire 55 where it finds return to source of energy. Corresponding conditions are obtained with an excess of current in wire 71 over 75, the difference in current in every case finding a return to wire 55 through magnet 86. Wire 55, it will be noted forms one side of a transmission system and also forms the neutral conductor for the three wire circuit operating magnets 85 and 86. This wire is, in fact, the equivalent of a common or ground to both of these circuits and may be grounded.

The end of the crossover α , by the mechanical connection represented by the dotted line 202 operates the double pole switches 211 and 211' and single pole switch 211'', and the end β , by connection 203 operates switches 211, 211' and 211''. Also, lever 90, through crank 201 and connection 204 operates double pole switches 250 and 251, these switches changing position with a corresponding change of position of the lever. The armature 88 swings in the magnetic yoke 87 between magnets 85 and 86 and to its outer end is connected the vertical rod 89 designed to engage a slot in lever 90 when the armature is down as shown and to release this slot when the armature is up or raised by magnet 85, thus forming an electric lock on the lever restricting its

movement and consequently the movement of locking dog 92 affecting an adjacent lever 91 and dog 93 may be similarly employed as is well understood in mechanical interlocking.

70

It will be seen that in the extreme positions switches 210 and 211 make contact with resistance 80 or 81 and in the intermediate position the switch circuit is open. Now resistance 80 is greater than 81 and it will be noted that with the crossover in the position shown there is in the upper wire a minor resistance 81 at switch 210 and a major resistance 80 at switch 211, while in the lower wire there is a major resistance at switch 210 and a minor resistance at switch 211, the sum of these resistances in each side of the main circuit therefore are equal so that the current in each side will be balanced and there will be no current in magnet 86 and magnet 85 will release the lock on lever 90. Now suppose that one end of the crossover moves in response to the lever and the other end (say end b) fails to move, then there will be in the upper wire a major resistance at both switches 210 and 211, while in the lower wire there will be a minor resistance at both these switches, that is, the resistance in one side of the circuit is increased and in the other side decreased, the excess current due to this difference in resistance in the lower wire finding a circuit through magnet 86 and wires 65, 62, 55 and 60 to the center of transformer 58. The magnetic circuit of magnet 86 is designed to have a greater attraction for armature 88 than magnet 85, in which gravity also assists so that current in magnet 85 cannot raise the armature when magnet 86 is energized.

95

The effect of a leakage from an adjacent circuit such as y , can be traced from battery 102, wire 155, switch 250, wire 171, cross connection y , wire 75, resistance 81, wire 76, magnet 85, wire 78, magnet 86, wires 65, 62 and 63 to other side of battery 102. A corresponding circuit will be established by any other leakage on the main circuit in which the source of energy connects to the common or ground wire 55.

110

In application B, the crossover mechanism is operated by motor 110 from batteries 101—102. The mechanism may be used in duplicate at both ends or one mechanism may operate both ends. The operating circuits can be traced from battery mains 154 and 155 to polechanging switch 250 operated by lever 90, wires 171, 175 and connections 171—175^a to safety relay 186. This relay is wound with opposing coils and connections from these coils are continued to polarized operating relay 185 as shown, a central point in the winding of this relay connecting to wire 61 and to a central point between batteries 101 and 102 by wires 60, 55, 130

115

120

125

130

62 and 63. The currents in the safety magnet, when they are equal, neutralize each other so that its armature is not attracted and the polarized armature 124—125 of operating relay 185 responds to the direction of the current in wires 171 and 175 as determined by the position of the pole-changing switch 250.

The motor runs in both directions to move 10 the switch points in either direction and opens its own circuit when the movement is completed. Its circuit may be traced from wire 117, armature contact 125, wire 118, safety magnet contact 123, wire 120, motor 15 armature 110, wire 121, safety magnet contact 122, wire 119, polarized contact 124, wire 116, cut-out switch 112, wire 114, motor field 111, and wire 113 to wire 171. When the motor completes the movement 20 the cut-out switch 112 is changed to the position shown establishing the motor circuit for a movement in the opposite direction when the polarized contacts 124 and 125 change position; a change which also re- 25 verses the direction of the current in the armature with relation to its field. The novel features in this arrangement consist in the use of the safety magnet 186 to guard against false operation as explained in connection with application A, also its operation 30 in combination with the other circuits.

Application C differs from application A in the use of a polyphase relay in place of the operating magnet 85 and in the fact that 35 the main circuit is controlled at three points.

The winding of the polyphase relay connected to the main circuit by wires 73 and 77 is indicated by the coil 94 and the coil 97 which is shown in quadrature phase relation 40 is connected to the local circuit. The main circuit is similar to that in application A, analogous reference characters being used for similar parts but distinguished by the exponent ('). At switch 211, however 45 the resistance coils 81' are omitted and these coils are inserted at switch 251 operated by the lever. In the latter case however, the movement of the lever merely shunts one or the other of these resistances as for instance 50 the resistance 81' is shunted in the upper wire as shown but is included in the lower wire. From this arrangement it will be noted that the sum of the resistances in each wire is, under normal conditions, equal and 55 that the corresponding movement of switch 251 balances the circuit established by switches 210' and 211'.

A middle point of coil 94 connects by wire 78 to safety magnet 95 and by wire 64 and 62 60 to common wire 55. An unequal flow of current in the main circuit energizes safety magnet 95 which attracts armature 48 opening the circuit of the local phase 97 on wire 98. This phase is supplied from the mains 65 51—52 by wires 98 and 99. As shown, the

polyphase relay consists of a squirrel cage rotor 96 counterweighted to open the contacts 96' when either phase is inactive. These contacts close a circuit between wire 155 and 220 operating the signaling device 70 231 from battery 101—102.

In each of the applications described both wires of the circuit are controlled. In application D, the same results are obtained by controlling only one wire of the circuit, and 75 the safety relay is required to make a preliminary movement before the relay in the main circuit can be energized.

The main circuit as shown can be traced as follows:—battery wire 154, resistance 180, 80 wire 131, switch 210'', wire 132, switch 211'', wire 133, wire 134, relay contact 135, wire 137, relay 138, wire 140, resistance 183 to battery wire 155. The safety relay 139 is connected in this circuit between wire 140 85 and 65' and connects to the middle of the battery by wires 62 and 63. Relay 139 remains deenergized when there is an equal drop of potential from each battery 101—102 in the main circuit to wire 140, that is: assuming the voltage of the batteries is equal, when the resistance 183 is equal to the combined resistance of relay 138 and resistance 180. Should a cross π develop between wires 132 and 154 this cross will shunt the resistance 180 and unbalance the circuit causing 90 relay 139 to energize.

The signal device 231' is controlled by circuit from battery wire 154, relay contact 226, wire 222, relay contact 225, wire 223 and 100 wire 155 to battery. This device is thus energized when relay 138 is energized and relay 139 deenergized. The signaling device 232 is controlled by battery from wire 154, relay contact 226, wire 222, front contact 225 105 of relay 139, wire 224 and wire 155 to battery. This device therefore responds to a condition of unbalancing with relay 138 energized, such for instance, as would occur with switch 210'' in either extreme position 110 and switch 211'' moved half way to include resistance 181 thus securing the desired unbalancing, that is to say, relay 139 responds to switch 211'' when switch 210'' has established a circuit.

Normally relay 139 is deenergized as shown but when relay 138 is deenergized this relay is energized due to the unbalancing of the main circuit, this condition remains until the main circuit is reestablished. The circuit of relay 138 when deenergized is opened at contact 135 and cannot be established until relay 139 is energized which insures that this relay is always operative. Thus the main circuit from wire 134 is closed at 136, 125 connecting to wire 137 and relay 138. In wire 137 a resistance 182 is inserted causing an unbalancing of the main circuit and thus maintaining relay 139 energized until relay 138 picks up and closes contact 135. This 130

contact shunts resistance 182 out of circuit and relay 139 is thereby deenergized.

Attention is called to the fact that resistance 180 is at one extreme end of the circuit 5 and resistance 183 at the battery end, any leakage intervening between these points therefore will cause unbalancing.

It should be noted in connection with application C that the polyphase relay in the 10 main circuit responds only to alternating current whereas relay 95 in the auxiliary circuit responds to current of any characteristic; this also applies to relay 186, application B. It is thus possible to make the 15 relays in the main circuit selectively responsive to a current of a particular characteristic and make the safety relay responsive to current from any particular source.

A consideration of this invention will 20 show that instead of providing a remote controlled apparatus responsive to a wide operating margin, it is responsive only to a predetermined operating effect.

Having thus described my invention, I 25 claim:—

1. In combination, a main circuit including a source of energy, a plurality of resistances and an electric translating device, an auxiliary circuit incorporating said main 30 circuit and another conductor and including an electric translating device, part of said resistances disposed in said main circuit close to said source of energy and part disposed close to said translating device, said resistances bearing a definite relation to 35 each other in said circuit.

2. In combination, a main circuit including a source of energy, resistance coils, an electric translating device, and two conductors between said source of energy and said translating device, an auxiliary circuit incorporating said main circuit and another conductor and including an electric translating device, said resistance coils being disposed 40 in each conductor of said main circuit and of different values and so arranged that the sum of the resistances in each conductor is equal.

3. In combination, a main circuit including a source of energy, resistance coils and controlling switches, an electric translating device, and two conductors between said source of energy and said translating device, an auxiliary circuit incorporating said 50 main circuit and another conductor and including an electric translating device, said switches by their position varying the resistance in said main circuit and when in a certain position relative to each other the 55 sum of the resistances in each conductor of said main circuit is equal.

4. In combination, a railway track, track switches thereon, a lever controlling the operation of said track switches, a main circuit including a source of energy, resistance 60

coils, controlling switches and an electric translating device having an armature, an auxiliary circuit incorporating said main circuit and another conductor and including an electric translating device having an armature, said controlling switches operated by said track switches and said armatures affecting the operation of said lever. 70

5. In combination, an apparatus, a power transmission system, a main circuit fed from 75 said transmission system and including an electric translating device having an armature with an auxiliary circuit incorporating said main circuit and one conductor of said transmission system and including an electric translating device having an armature, 80 said armature controlling said apparatus.

6. In combination, an apparatus, a power transmission system, a main circuit fed from 85 said transmission system and including resistances, controlling switches and an electric translating device with an auxiliary circuit incorporating said main circuit and one conductor of said transmission system and including an electric translating device, said 90 controlling switches varying said resistances by their position and said translating devices controlling said apparatus.

7. In combination, a power transmission system, a transformer connected to said system and feeding a main circuit which includes an electric translating device with an auxiliary circuit incorporating said main circuit and including an electric translating device, an intermediate point of the secondary winding of said transformer and said latter translating device connecting to one conductor of said transmission system. 95 100

8. In combination, an apparatus, a main circuit including a source of energy, resistance coils and an electric translating device, an auxiliary circuit incorporating said main circuit and another conductor and including an electric translating device, said 105 circuits controlling said apparatus, means including said auxiliary circuit for varying the effects obtained on said apparatus by varying the value of the resistance on one side of said main circuit with relation to the resistance of the other side. 110

9. In combination, an apparatus, a main circuit including a source of energy, resistance coils and an electric translating device, an auxiliary circuit incorporating said main circuit and another conductor and including 115 an electric translating device, said circuits controlling said apparatus, means including said auxiliary circuit for varying the effects obtained on said apparatus by varying the value of said resistance at one point in said 120 main circuit and means for canceling this effect at other points in this circuit. 125

10. In combination, an apparatus, a main circuit including a source of energy, resistance coils and an electric translating device, 130

an auxiliary circuit incorporating said main circuit and another conductor and including an electric translating device said circuits controlling said apparatus, means for varying said control by the presence of current in said auxiliary circuit and by the absence of current in one side of said main circuit.

11. In combination, a plurality of main circuits operated by currents of different characteristics and including electric translating devices, auxiliary circuits each incorporating one of said main circuits and another conductor and including an electric translating device, the translating device in each of said main circuits being selectively responsive to the characteristics of its respective current and the translating device in said auxiliary circuit being responsive to current of any characteristic.

12. In combination, an apparatus, a main circuit including a source of energy, resistance coils and an electric translating device, an auxiliary circuit incorporating said main circuit and another conductor and including an electric translating device said devices controlling said apparatus, means including said resistances for operating the translating device in said auxiliary circuit by varying the resistance in said main circuit when it is established.

13. In combination, a railway track, switches thereon, a lever controlling the operation of said track switches, a main circuit including a source of energy, resistance coils, controlling switches and an electric translating device having an armature; an auxiliary circuit incorporating said main circuit and another conductor and including an electric translating device having an armature, said track switches operating said controlling switches and said armatures affecting the operation of said lever, means including said resistance coils for introducing characteristics into said circuit to insure a coördinate action between said lever and said track switches.

14. In combination, an apparatus, a railway track, a track switch thereon, a main circuit including a source of energy, major and minor resistances, controlling switches and an electric translating device having an armature, an auxiliary circuit incorporating

said main circuit and another conductor and including an electric translating device having an armature, said track switch operating said controlling switches, and said resistances being so disposed in said circuit, that, according to the position of the track switch, a major or minor resistance is included in a conductor of said main circuit, 60 said armatures controlling said apparatus.

15. In combination, an apparatus, a railway track, a plurality of track switches thereon arranged to operate together, a main circuit including a source of energy, resistances, controlling switches and an electric translating device having an armature, an auxiliary circuit incorporating said main circuit and another conductor and including an electric translating device having an armature, said track switches operating said controlling switches and said resistances being so disposed in said circuit that when said track switches are in a predetermined position the sum of the resistances in each conductor of said main circuit is equal, 70 said armatures controlling said apparatus.

16. In combination, an apparatus, a railway track, track switches thereon, a controlling lever for said switches, a main circuit including a source of energy, major and minor resistances, controlling switches and an electric translating device having an armature, an auxiliary circuit incorporating said main circuit and another conductor and including an electric translating device having an armature, said track switches and said controlling lever each operating a controlling switch, said controlling switches when operated, changing the resistances in 80 said main circuit and said resistances being so disposed in said circuit that when said track switches and lever are in a predetermined position the sum of the resistances in each conductor of said main circuit is equal, 85 said armatures controlling said apparatus.

In witness whereof I have hereunto subscribed my name in the presence of two witnesses.
